CLAIM

The ornamental design for a hoodie pants as shown and described.

DESCRIPTION

FIG. 1 is a perspective view of a hoodie pants, showing my new design;

FIG. 2 is a front elevation view thereof;

FIG. 3 is a rear elevation view thereof;

FIG. 4 is a right side elevation view thereof of which the left-side elevation view is a mirror image;

FIG. 5 is a top plan view thereof;

FIG. 6 is a bottom plan view thereof; and,

FIG. 7 is an additional front elevation view thereof.

The broken lines in the drawings illustrate portions of the hoodie pants that form no part of the claimed design.

1 Claim, 6 Drawing Sheets
